[57] CLAIM

The ornamental design for a pneumatic tire tread and
buttress, substantially as shown and described.

DESCRIPTION

FIG. 1 is a perspective view, partly schematic, of a
pneumatic tire tread and buttress embodying my new
design, it being understood that the pattern is repeated
throughout the circumference of the tread and buttress,
as shown schematically by solid lines, and that the but-
tress pattern is repeated on the opposite side;
FIG. 2 is an enlarged, fragmentary developmental plan
view of the tread and buttress of FIG. 1; and
FIG. 3 is a sectional view of the tread and buttress,
taken substantially as indicated by line III—III of FIG.
2.

FIG. 1

FIG. 2

FIG. 3
